UNITED STATES PATENT OFFICE.

LEONARD A. SMALLWOOD, OF BIRMINGHAM, ENGLAND; ALFRED SMALLWOOD
ADMINISTRATOR OF SAID LEONARD A. SMALLWOOD, DECEASED.

HEAT-DIFFUSER FOR BOILER-FLUES.

1,082,829.

Specification of Letters Patent.

Patented Dec. 30, 1913.

Application filed June 18, 1910. Serial No. 567,640.

To all whom it may concern:

Be it known that I, LEONARD ALFRED SMALLWOOD, a subject of the Kingdom of Great Britain, residing at Tamworth House, 5 Livingstone Road, Handsworth, Birmingham, in the county of Warwick, England, tube manufacturer, have invented a certain new and useful Heat-Diffuser for Boiler-Flues, of which the following is a specification.

This invention relates to the furnaces of boilers of the Lancashire, Cornish, marine or other similar type and particularly to boilers in which the furnace gases issuing 15 from the grate are directed in a body to impinge upon a large surface of boiler plate and to thereby transmit their heat for purposes of evaporation.

The object of the present improvements 20 is to provide for the better utilization of the heat for purposes of steam generation than has heretofore been the case, and with this object in view means are incorporated whereby a zone of extremely high heat 25 intensity is generated and maintained in the near vicinity of the surface to be heated.

The improvements are also such that the smoke is effectively consumed and an economy in fuel secured by reason of the completeness of combustion coupled with the efficient means of transmitting the heat to the heating surface of the boiler.

I carry out the present invention by building a lining of refractory material in close 15 relation to the boiler plates in such a manner that while an inter-space or spaces is left between the refractory material and the boiler plate, air or furnace products is or are precluded from circulating in such 20 space or spaces, which latter are thereby enabled to maintain a particularly high temperature and at the same time to provide for the efficient transmission of heat to the boiler plates for purposes of steam generation. The brickwork may conveniently take the form of an arch or lining commencing at or near the bridge and extending backwardly as far as may be required to obtain complete combustion. The space or spaces between the lining and the boiler plate are open at the rear, but closed at the front, and the refractory brickwork becoming readily incandescent radiates its heat to the heating 25 surface of the boiler.

In order that this invention may be clearly 55 understood and more readily carried into practice, reference may be had to the appended two explanatory sheets of drawings, on which:—

Figure 1 shows a longitudinal section of a 60 boiler having a flue provided with the improved lining. Fig. 2 is an enlarged sectional elevation of the improved lining with metal radiators provided around the whole of the internal periphery of the flue. Figs. 65 3 and 4 are cross sectional elevations of the flue and lining shown in Figs. 1 and 2 respectively. Fig. 5 is a perspective view of one of the blocks or bricks used in the construction of the improved lining. Fig. 6 is a 70 perspective view of one of the bricks which is used as hereinafter described.

In a convenient embodiment of this invention such as illustrated by the drawings, the desired spaces between the brickwork A and 75 the boiler plate B may be formed by providing longitudinal channels a^1 in the upper part of the bricks a^2 such channels a^1 being in alinement and forming gutters which extend the length of the arch A and which are 80 closed by a suitable formation d^1 of the front bricks D as shown in Fig. 6 or by a separate annulus e shown in Figs. 1 and 2. The channels or gutters may be isolated one from another but preferably the side webs a^3 of the 85 bricks are suitably cut away at a^5 to provide a means of communication between the adjacent channels. By cutting apertures in the side webs a^3 in this manner each brick may be left with four or six legs a^4 which 90 butt against the boiler plate B and thereby maintain the desired formation of the arch.

In order to assist the radiation of heat from the refractory material A to the heating surface of the boiler, it may be desirable 95 to arrange metal strips C in the channels of the brickwork; these strips becoming heated by the heat of the refractory material more readily radiate the heat, while at the same time by reason of their close proximity with 100 the water they are not subject to such overheating as would fuse or burn them. The metal strips may in some cases take the form of linings which are disposed within the channels of the refractory material, but in all 105 cases they are precluded from deterioration by the isolated nature of the channels or gutters whereby no oxygen or furnace products

2

are enabled to circulate therein. Such metal strips may be arranged in all the channels or in any desired proportion thereof, in which latter case a depending rib c^1 or ribs is furnished for their support.

It is obvious that a similar formation of the refractory material may if desired be applied to the outer shell of the boiler, to be heated by the gases in their passage 10 through the flues within the settings but in view of the reversed contour of the boiler plates additional security may be necessary for satisfactorily maintaining the fire-bricks in place.

15 What I claim as my invention and desire to secure by Letters Patent is:—

1. In combination with a boiler having a flue therein, of a cylindrical lining disposed in said flue and composed of brickwork of 20 refractory material, said brickwork having relatively reduced portions engaging the flue and hollowed-out portions to form an air chamber between the refractory material and the flue, and metallic heat conducting 25 elements disposed in said hollowed-out por-

tions and arranged to be out of contact with the flue.

2. In combination with a boiler having a flue therein, of a refractory lining in said flue having reduced portions engaging the flue to support the lining therein, and metal 30 heat conducting elements between the lining and said flue and out of contact with the flue, substantially as and for the purposes set forth.

3. In combination with a boiler having a flue therein, of a refractory lining in said flue having reduced portions engaging the flue to support the lining therein, and metallic heat conducting means between the 40 lining and said flue and out of contact with the flue, substantially as and for the purposes set forth.

In witness whereof I have hereunto set my hand in the presence of two witnesses. 45

L. A. SMALLWOOD.
